UNITED STATES PATENT OFFICE.

SIMON SIMONEAU, OF CHICOPEE FALLS, MASSACHUSETTS.

HAT HOLDER.

Application filed October 5, 1925. Serial No. 60,607.

To all whom it may concern:

Be it known that I, SIMON SIMONEAU, a citizen of the United States, residing at Chicopee Falls, in the county of Hampden and State of Massachusetts, have invented new and useful Improvements in Hat Holders, of which the following is a specification.

This invention relates to improvements in hat holders, the general object being the provision of a spring strap to be detachably secured to objects of flat and circular formation and having depending therefrom a spring clip for grasping, holding, and supporting a hat thereon in the instance of theaters, parlor cars, and the like.

With the above and other objects in view, the invention further includes the following novel features and details of construction, to be hereinafter more fully described, illustrated in the accompanying drawing and pointed out in the appended claim.

In the drawing:—

Figure 1 is a fragmentary elevation of a car seat and showing my present invention applied thereto.

Figure 2 is a detail perspective of my invention per se.

Referring to the drawing in detail, wherein like characters of reference denote corresponding parts, the reference character 10 indicates a steel strap of springy propensity arranged in the formation of a circle and normally having a correspondingly offset end portion 11 tensioned against each other in the position as clearly illustrated in Figure 2 of the drawing and including openings 12 arranged upon the side and extending longitudinally thereof and within which openings 12 being linked or otherwise secured, a ring 13 also extending through an opening 14 provided in one arm of a spring clip or fastener, as indi-

cated at 15, the jaws thereof being capable of relative spring tensioned expansion in 45 the gripping of the brim 16 of a hat 17, as clearly illustrated in Figure 1 of the drawing, or some other object to be supported when the strap 10 straddles the upper side of a chair or seat back 18 in the manner as 50 illustrated.

Although I have shown and described my invention as applied to a seat or chair back 18 in the supporting of a hat 17 thereupon, it is to be understood that I do not limit 55 myself to this limitation of the showing but that the said invention may be applied equally as well to bodies of flat and round configuration with little difficulty owing to the elasticity of the straps 10. Owing to 60 the like propensities of the spring clip or snap 15 that most any article may be grasped and held within the jaws thereof and against accidental displacement therebetween.

The invention is susceptible of various changes in its form, proportions and minor details of construction, and the right is herein reserved to make such changes as properly fall within the scope of the appended claim.

Having described my invention what is claimed is:—

A hat holder of the character described comprising a spring clip arranged in the formation of a circle and terminating in like abutting end portions and providing a pair of aligned openings in one side thereof, a ring extending to the openings in the strap, and a spring clip having an opening provided in one of the companion handle members therefor and receiving the ring therein in the supporting of the latter thereon.

In testimony whereof I affix my signature.

SIMON SIMONEAU.
